Inventor

Lee H. Miller

By Bair & Freeman

Witness
Lynn Latta

UNITED STATES PATENT OFFICE.

LEE H. MILLER, OF FORT DODGE, IOWA.

GRAIN DOOR.

Application filed June 18, 1923. Serial No. 646,069.

To all whom it may concern:

Be it known that I, LEE H. MILLER, a citizen of the United States, and a resident of Fort Dodge, in the county of Webster, 5 State of Iowa, have invented a certain new and useful Grain Door, of which the following is a specification.

The object of my invention is to provide a grain door of simple, durable, and comparatively inexpensive construction whereby it may be manufactured and marketed at a comparatively low cost.

More particularly, my invention relates to a grain door structure comprising a number 15 of sections, each capable of movement independently of the other and means for holding any one or all of the door sections in their open position.

Still another object is to provide a lever 20 device secured to the lowermost door, which may be manipulated for raising the door sections.

Still a further object is to provide a latch structure for connecting the door sections 25 together whereby they may be moved as one unit.

With these and other objects in view, my invention consists in the construction, arrangement and combination of the various 30 parts of my device, whereby the objects contemplated are attained, as hereinafter more fully set forth, pointed out in my claims, and illustrated in the accompanying drawings, in which:

Figure 1 is a side elevation of a portion of a box car with my improved grain door 35 structure shown thereon.

Figure 2 is a central, sectional view taken on line 2—2 of Figure 1.

Figure 3 is a detail, sectional view taken 40 on line 3—3 of Figure 1.

Figure 4 is a detail, sectional view taken through a portion of the door sections showing the latch connection.

Figure 5 is a detail, sectional view taken 45 on line 5—5 of Figure 1.

Figure 6 is a detail, side view of one of the hinge connections between the slats of the door sections.

Figure 7 is a detail, sectional view showing 50 a portion of the lever structure.

Figure 8 is a sectional view taken on line 8—8 of Figure 7.

Figure 9 is a detail view of the locking

means for holding the door sections in their 55 raised or open position.

Figure 10 is a sectional view taken on line 10—10 of Figure 9; and

Figure 11 is a detail, perspective view of the clasp for holding the lever in locked 60 position.

In the accompanying drawings, I have used the reference numeral 10 to indicate generally a box car which is provided with ordinary door openings 11 in each of its 65 sides. On each side of the door openings 11 are the uprights or supporting beams 12. The siding 13 is secured to the uprights 12. Secured to the inner sides of the uprights 12 are the posts 14. The posts 14 are narrower than the uprights 12. Fixed to the posts 14 are channel-shaped guide members 15 and 16.

The channel shaped guides 15 and 16 are arranged in pairs, that is, two channel 75 shaped guides 15 serve for one of the door openings 11, and two channel shaped guides 16 serve for the other door opening. The channel shaped guides 15 are provided with a vertical portion which rests against the 80 posts 14 and with a horizontal portion, as clearly shown in Figure 2 of the drawings.

The horizontal portions of the guides 15 are supported by straps 17, which are secured to a cross piece 18 at their upper ends. 85 The upper free end of the guides 15 are secured to the side of the box car, as at 19. A rod 20 extends from one of the guides 15 to the other guide 15 for holding them properly spaced apart.

The guides 16 are provided with horizontal portions as well as vertical portions. The horizontal portions of the guides 16 are arranged below the horizontal portions of the guides 15, as clearly shown in Figure 2. 95

The horizontal portions of the guides 16 are supported by straps 21 which are supported from the channel 15. A rod 22, at the inner upper ends of the guides 16, holds them in proper spaced relation.

Slidably mounted within the pair of guides 15 and within the pair of guides 16 are the door sections A, B, and C. Each section is composed of a plurality of slats or narrow members 23 which have their lower surfaces grooved and the upper surfaces curved so as to snugly fit together, as shown in Figure 4 of the drawings. The

adjacent strips 23 are connected together by means of the hinges 24.

Each of the strips 23 is provided with reinforcing caps 25, secured in position by means of the rivets 26. The channel shaped guides 15 and 16 are secured to the posts 14 by means of the bolts 27, which are provided with countersunk heads so as to not interfere with the free movement of the door sections.

For connecting the sections A, B, and C together so that they may be operated as a unit, I provide coacting latch members 28 and 29. The member 28 is pivoted by means of a pin 30 to a member 31, which in turn is secured to one of the strips 23.

The member 29 is secured to one of the strips 23 and is provided with an opening 32 so that the lower end of the latch member 28 may project therein for locking the sections together, as clearly shown in Figure 4 of the drawings. The latch member 28 is so arranged that it will normally remain in locked position.

From the construction of the door sections, it will be seen that any one of the sections may be slid within the channel shaped guides to position where the door openings 11 will be clear. In Figure 2 of the drawings, I have shown one of the sections C in raised position.

Secured to sills 33 are the reinforcing plates 34. The reinforcing plates 34 are provided with a curved portion 35 which fits into the groove of the underside of the lowermost strip 23.

The sills 33 are each provided with recesses 36 in which is mounted a channel shaped container 37. The channel shaped container 37 is secured in position by means of the screws 38.

A number of rollers 39 are mounted on the pins 40, which are journaled in the walls of the container 37. The purpose of the rollers 39 will hereinafter more fully be set forth.

Secured to the lowermost strip 23 is a lever 41 mounted on the bolt 42. The lever 41 is provided with a cam surface 43 which is designed to abut against the rollers 39 for raising the door sections.

In this connection, it may be mentioned that when the lever 41 is swung to position, shown in dotted lines in Figure 7 of the drawings, it will cause the door sections to be raised.

A clasp 44, shown in Figure 1 of the drawings, is used for engaging the upper end of the lever 41. The upper end of the lever 41 is provided with an opening so that a seal may be placed therethrough for sealing the door sections against opening.

The latch members 28 are also provided with small openings 45 so that a seal may be passed therethrough.

In order to hold any of the door sections in their raised position, I provide the following means. Secured to each of the uprights 12 by means of the bolts 46 is a bar 47.

The bar 47 is provided with a slot 48. The portion of the bar that is provided with a slot 48 is offset so as to be spaced from the upright 12.

A pair of levers 49 and 50 are secured to the bar 47 by means of the bolts 51 and 52. The bolt 52 is mounted in the slot 48 and is capable of travelling therein.

The outer free ends of the levers 49 and 50 are joined together by means of a bolt 53. The lever 49 is slightly curved, as shown in Figure 9.

The pair of levers 49 and 50, when in the position shown in Figure 9, will project into the path of movement of the door sections and prevent the door sections from moving downward.

In order to clear the levers 49 and 50 from the door opening, it is necessary to slide the bolt 52 in the slot 48, thus bringing the lower end of the lever 49 to the position shown in Figure 9, in dotted lines.

It will be seen that I have provided a very efficient means for holding the door sections in their raised position. My structure can be used for grain doors or other buildings.

Some changes may be made in the construction and arrangement of the various parts of my invention without departing from the real spirit and purpose of my invention, and it is my intention to cover by my claims, any modified forms of structure or use of mechanical equivalents, which may be reasonably included within their scope.

I claim as my invention:

1. In a device of the class described in combination with a door opening, a pair of channel shaped guide members arranged adjacent to the sides of the door opening, said guide members having their upper ends curved away from the door opening, a plurality of door sections slidably mounted in said guide members, each door section being independent of the others and each door section comprising a number of slats hingedly connected together for permitting them to slide in the curved portions of the guide members, a lever secured to the lower section for assisting in the raising thereof, and locking means for holding said door sections in open position, said locking means including a pair of pivoted levers, one of which is slidably mounted relative to the other so that it can be moved to position where it will project into the door opening as and for the purposes stated.

2. In a device of the class described in combination with a door opening, a pair of channel shaped guide members arranged adjacent to the sides of the door opening,

said guide members having their upper ends curved away from the door opening, a plurality of door sections slidably mounted in said guide members, each door section being independent of the other and each door section comprising a number of slats hingedly connected together for permitting them to slide in the curved portions of the guide members, a lever secured to the lower section for assisting in the raising thereof, and locking means for holding said door sec-

tions in open position, said locking means including a pair of levers, one of which is slidably mounted, said levers having their free ends pivoted together, said pair of 15 levers when in one position being arranged to project out into the door opening and when in another position to permit the door to be moved independently thereof.

Des Moines, Iowa. March 19, 1923.

LEE H. MILLER.
